AIR CLEANER

Stanley L. Cox, Cincinnati, Ohio, assignor to The Kirk & Blum Manufacturing Company, Cincinnati, Ohio, a corporation of Ohio

Application December 20, 1949, Serial No. 134,021

8 Claims. (Cl. 183—21)

1

The present invention relates to a dust collector and air cleaner and has for an object the provision of a device of this kind which is compact in structure, highly efficient in air cleaning and economical of power.

Another object is to provide a combination centrifugal dry and wet air cleaner wherein all of the heavier particles and nearly all of the finer particles including microscopic particles are removed by essentially dry centrifugal separation, while the entire volume of air treated, containing the small remainder of very fine particles only, is employed to set up a water spray of large volume for wetting the remaining entrained particles, to centrifugally remove the water and wetted particles and to discharge dust-free and water-free air.

Another object of the invention is to provide within a casing, resembling a cyclone type collector, a series of concentrically spaced and longitudinally related cylindrical walls and cylinders for effecting the foregoing dust removing and air cleaning operations continuously and at minimum power cost.

Still another object of the invention is to provide a device of the class described with a lower contained body of water, or other liquid, as a common depository for all of the dust and solid matter that is removed from the air.

These and other objects are attained by the means described herein and disclosed in the accompanying drawings, in which:

Fig. 1 is a side elevational view of a device embodying the invention, parts being broken away to disclose the interior structure.

Fig. 2 is a top plan view of the device shown in Fig. 1.

Fig. 3 is a sectional view taken on line 3—3 of Fig. 1 and showing sectionally a sludge ejector associated with the liquid containing bottom of the device.

As shown in the drawings the device comprises a hollow casing indicated generally at 14 and made up of an upright, outer cylindrical wall 15 which is supported adjacent its bottom by a plurality of suitably connected legs 16 which in turn are secured at the bottom to any suitable support means such as a base frame 17.

A circular top 18 has a pressure tight connection at its edges with the top edge of outer wall 15 and a clean air outlet pipe 19 passes concentrically through the top 18 and extends above and below said top.

An inverted frusto-conical bottom 20 is secured at its top to the bottom of the cylindrical

2

outer wall 15 and is provided with a bottom sludge outlet which may, if desired, be closed simply by a threaded cap 21 as illustrated in Fig. 1.

A cylindrical inner wall 22 is connected at its top in pressure tight relation to the bottom interior face of the top 18 of the casing and it depends concentrically with wall 15 and terminates in a free bottom edge 23 a short distance above the juncture of wall 15 and bottom 20. Outer wall 15 has a rectangular opening therethrough which receives the rectangular extended end 24 of an air intake coupling or boot 25 for tangentially directing intake air to the inner face of outer wall 15. It will be seen that air to be cleaned is entered tangentially into the top of annular space 26 between the walls 15 and 22 so that air borne particles are subjected to centrifugal force and become concentrated on the inner face of outer wall 15 as the air travels centrifugally in its progressively descending path within the said space 26 until it reaches the bottom edge 23 of the inner cylindrical wall 22.

The bottom 20 is adapted to contain water or other suitable liquid 27, and the top level of the body of water 27 normally assumes a position approximately as indicated by the dashed line L—L when the device is inoperative. A pair of cylinders 28 and 29 are arranged in the lower part of the cylindrical casing, the larger cylinder 28 lying concentrically intermediate the walls 15 and 22 while the smaller cylinder 29 is disposed concentrically of and inwardly of the inner cylindrical wall 22. These cylinders or rings 28 and 29 are substantially equally spaced from the opposite faces of cylindrical wall 22. The cylinder or ring 28 has its bottom edge 30 depending well below the water level L—L and is supported by any suitable means such as rods 31 which are welded or otherwise fixed to the inclined wall of bottom 28. The circular upper edge 32 is located above the normal water level L—L and may in most instances extend above the level of bottom edge 23 of inner cylindrical wall 22. Cylinder 29 is suspended with its bottom edge 33 well below the water level L—L and has its top edge 34 at some distance above the bottom edge 23 of inner cylindrical wall 22. The cylinder 29 is supported from the bottom interior thereof by a plurality of bars 35 which are welded or otherwise secured to the bottom end of a vertical suspension rod 36. Spacing studs 37 serve to adjust and maintain a concentric relation between the cylinder 29 and wall 22. Rod 36 passes upwardly through outlet pipe 19 and through the closed top 38 of said outlet pipe. An

exteriorly mounted bridge 39 on the top 38 is centrally perforated to receive the threaded top end 49 of the rod 26 and nuts 41 located above and below the bridge 39 provide for ready vertical adjustment of said rod and the cylinder 29 suspended therefrom. A circular plate 42 is fixed on rod 26 which passes through the center thereof, the diameter of plate 42 being only slightly less than the inner diameter of fresh air outlet pipe 19 with which it is axially centered.

Fixed to the inner circumferential surface of cylindrical wall 22 is an annular baffle ring 43 the minimum diameter 44 of which is at the lower edge and is approximately equal to the diameter of the fresh air outlet pipe 19 above it. Baffle 43 is in practice made up of two beveled rings connected together and forming an inverted right-angled groove overhanging the space between cylinder 29 and the inner cylindrical wall 22.

A pair of intersecting sheets or strips 45 are fixed vertically edgewise to bottom 20 and they are submerged with their tops approximately level with the bottom edge 32 of cylinder 29.

Passing through bottom 20 is an internally threaded sleeve 43 which allows an externally threaded pipe 47 to be adjusted vertically therethrough. The pipe 47 may have an unthreaded extension 48 at the top which is open and constitutes a vertically adjustable overflow for the water 21.

Clean air outlet pipe 19 has a discharge opening in the side thereof extending from the top downwardly, and an eccentric scroll 49 extending therefrom. A rectangular outlet tube 58 embodies said scroll as one side thereof and a plate 51 tangential to the exterior of pipe 19 as the other side thereof. The space between is closed by top and bottom walls respectively and these are developed into a coupling or boot 52 to which the suction end of a power fan 53 is connected.

A pipe coupling 54 is connected to top 18 to receive a piped supply of tap water or other liquid whereby liquid may be flowed down the inside face of wall 22. Another pipe coupling 55 is similarly mounted to provide a water flow over the inside face of wall 15. Either or both may be employed in filling the bottom 20 or in re-establishing, or in maintaining the desired water level such as L-L or a level to be maintained by the adjusted overflow pipe 47-48. The connections 54 and 55 may be used during operation of the device under some conditions but are not required for the actual cleaning of the air.

The device of the invention may be installed wholly inside the building or shop where the waste or dust is liberated by machines or other apparatus and the air discharged from the device may be found in many instances to be considerably cleaner than the outside atmosphere in the vicinity.

The installation of the device will be understood to include a conveyor conduit or system of conduits extending from one or more sources of dust and connected to coupling 25 in known manner. Velocity air movement is established by operation of a suitable suction fan such as 53 which has its intake port connected by a suitable conduit 59 to the coupling boot 52 which leads from the clean air outlet 19. The discharge from the fan 53 may be carried, if desired, to a suitable point for localized release into the atmosphere by means of a conduit or conduit system (not shown).

In operation the fan 53 is actuated and withdraws air from the interior of pipe 19 and the center chamber 56 below it. The dust laden air to be cleaned is thus drawn from one or more sources (not shown) and enters as a velocity air stream through coupling or boot 25 from which it is charged tangentially into annular chamber 26 adjacent its top. The centrifugal force of the air stream separates all heavy particles and very nearly all of the fine dust particles, including part of the microscopic particles by stratifying the entrained dust and condensing the discrete dust particles against the inside face of wall 15. Those particles which may contact each other and form a larger and heavier unit mass may descend along wall 15 at a greater rate than the spiraling air stream in which they accumulated. When the entrained material is relatively difficult to wet, a selected flow of water from connector 55 may be passed down over the inner face of wall 15 to assist in the wetting and to aid in collecting the dust into heavier masses for earlier separation from the air stream thereby washing the dust away to further reduce dust loading at the water spray point hereinafter described.

When the downwardly spiraling stream has reached the top edge 32 of cylinder 28 approximately 95% of the large dust particles still entrained will be located in the outer portion of the air stream and will descend between cylinder 28 and the wall 15 and be violently projected angularly onto the surface of the water between those members and are effectively separated from the air stream.

The pressure of the air within annular chamber 26 is greater than that in the cylindrical chamber 56 due to the fact that the entire volume of carrier air must still pass through the relatively restricted area between the top of the liquid body 27 and the lower edge 23 of wall 22. As a result of this pressure the water level in the annular zone between the outer circumference of cylinder 29 and the wall 15 is depressed while the water level inside cylinder 29 is raised to establish a static pressure balance.

The entire volume of velocity air from annular channel 26 must now pass through the restricted annular zone between cylinder 28 and wall 22 with increased velocity and directly onto the depressed surface D of the water. As a result a considerable volume of water is picked up by the air stream which now has entrained therein only about 5% of the originally contained dust.

The action of the spiraling air stream on the water imparts a violent and turbulent vortical action on the surface of the water impinged by the air stream. The fixed and submerged baffle sheets 45 confine the violent action effectively to a relatively shallow top layer of the water so that the force of the air stream is not wasted in setting the entire mass 27 into whirling motion. The water below sheets 45 is relatively tranquil so that the dust particles entering at the several places may settle quietly and form a denser sludge at the bottom of the water pool 27.

The direction of the air stream is now abruptly changed to an upward spiral flow due to the location of cylinder 29. There is thus set up a violent turbulence on the depressed surface D of the water between cylinders 28 and 29 and, due to the restriction of the flow area, a large volume of the turbulent water is picked up in the air stream, and the upstanding cylinder 29 and depending wall 22 form between them a narrow

annular channel directing the flow upwardly against the inverted V-trough with great violence. A very dense water spray is thus formed and the greater part of the water with the now completely wetted particles is deflected into the center of cylinder 29 by the combined rebound of the water and the pressure flow of the air. The air and any entrained spray water continues a whirling and upwardly travel toward air outlet 19 and centrifugal force separates entrained water and throws it against the inside surface of wall 22 where it collects and runs down over the upper bevel ring 43 and spills into the center of cylinder 29. The circular baffle plate 42 prevents short circuiting of the pressure air from the spray forming area to outlet pipe 19 so that water removal is assured. A water flow at 54 may be had to add to the water that is thrown onto wall 22 by the action of the air and this aids in washing the wetted microscopic particles down ultimately into pool 27.

The scroll 49 adjacent the top outlet 50 assists materially in maintaining an extremely active whirling motion in the air within pipe 19 and the chamber 56 and thus augments the centrifugal separation force which carries through from annular chamber 26.

The air finally reaching fan 53 is free of dust or waste particles and of water droplets. A slight increase in humidity of the discharge air over that of the intake can be detected by instrument but is not otherwise apparent. Under many industrial environments the discharge air is cleaner and more healthful than the surrounding outside atmosphere and is therefore desirably distributed interiorly of the building. The device is conveniently contained within the building under practically all operating conditions when water or other safe liquid is used as the medium in which the dust is collected in the form of sludge.

The nature of the materials may produce a collected sludge that is essentially a waste product and as such is more easily handled as sludge in either condensed or diluted form. In some instances the collected dust particles removed from the intake air stream may contain valuable materials that warrant further cleaning and separation. The dust of precious metals is one example of a sludge ingredient that justifies separation and recovery by further treatment. Wood dust, cellulose fiber particles and kindred materials collected in quantity may warrant processing for by-products or may be drained and ultimately burned or otherwise disposed of without troublesome scattering.

For installations wherein large quantities of dust materials are collected it should be understood that the automatic removal of sludge should be provided for in a manner that may be carried on continuously or intermittently during operation of the air cleaner. Any approved mechanism may be used for this purpose for example as indicated somewhat schematically in Fig. 3. Such a sludge ejector consists essentially of a conveyor housing H open at its top above the water level L—L in the device and communicating with the bottom interior of the member 20 through a chamber C which surrounds the clean out opening from which cap 21 of Fig. 1 is omitted. A power driven elevating conveyor E of any suitable type for example an Archimedean screw, or an endless belt with blades or buckets (not detailed) may be employed to carry away the settling and heavier collected material from the bottom of pool 27. The liquid flow through connections 54

and/or 55 may be adjusted to maintain the liquid level of the pool 27.

The overflow pipe 47—48 may be connected to a drain and may carry away fine particles that persist in floating on the surface.

From the foregoing it will be appreciated that the air cleaner of the invention operates as a combination cleaner in that the separation of approximately 95% of the entrained material in the intake air is effected by fundamentally a dry centrifugal separation process in the annular chamber 26, regardless of whether or not a liquid flow over wall 15 is used, and that the remaining approximately 5% of the total entrained dust (which is of finer and largely microscopic particle size) is dispersed widely in the entire original volume of entrained air which picks up a large volume of water and converts it into an extremely effective water spray beneath the annular inverted V-baffle formed by the ring 43. The dust loading in the wet spray operation is thus greatly reduced and the efficiency of the cleaning operation is correspondingly more effective. The increased effectiveness in practice results in reduced operational power costs as compared with wet collectors in which the intake air stream with all of its entrained dust is charged into a body of liquid. Moreover the said type of wet collectors have presented some difficulties in that they may not have the velocity stream appreciably varied to suit changing work load conditions without danger of allowing either some dust or some water to pass through with the discharge air. In contrast the device of the present invention may have its work load varied widely without requiring adjustment and without impairment of its air cleaning function. In no instance does the discharge outlet air stream contain any entrained water droplets.

40 What is claimed is:

1. An air cleaner comprising a centrifugal separator of the cyclone type including an outer cylindrical wall, a top, a vertical outlet air pipe extending concentrically therethrough for a distance above and below said top, a bottom forming a liquid tight closure for said casing serving to establish an open topped basin within the bottom of the casing, means to admit liquid into the casing whereby a liquid pool is established in said basin to a selected liquid level confined at its top within the lower end of the cylindrical outer wall, a pair of cylinders in the lower part of the casing concentrically spaced from the inner circumference of said outer wall and from each other, said cylinders having their lower edges and upper edges respectively disposed below and above the said liquid level in said pool basin, a cylindrical inner casing wall extending concentrically downwardly from the casing top and terminating intermediate the cylinders and below the top edge of the inner cylinder, an annular baffle secured on the inner circumference of said inner cylindrical wall and having a groove in the bottom thereof overhanging the top edge of the inner cylinder, means for introducing a dust laden velocity air stream tangentially into the annular space between the inner and outer cylindrical walls adjacent the top of the casing and means for exhausting air tangentially from the outlet pipe above the top of the casing.

2. In combination a cylindrical outer casing, a collector basin forming a water tight closure at the bottom of said casing, a top closing the upper end of said casing, an air outlet pipe extending through the top for a distance above and below

the top, a closure for the top of said outlet pipe, means including a scroll casing adapted for connection with a suction fan for exhausting air tangentially from the outlet pipe adjacent the top thereof, an inner cylindrical wall located concentrically intermediate the outlet pipe and the outer casing wall and extending from the casing top to a level slightly above the top of the collector basin, a pair of vertical cylinders spaced respectively concentrically within and without the circumference of the inner casing wall and having the bottom edges thereof terminating below the top of the pool basin, the top edge of the inner cylinder extending above the bottom of said inner cylindrical wall, an inverted V-shaped baffle secured to the inner circumference of said inner cylindrical wall in overhanging relation closely above the top of the inner cylinder and a circular baffle plate fixedly mounted above said inverted V-shaped baffle and having its circumference spaced concentrically from said inner cylindrical wall below the bottom of the outlet pipe.

3. In a device of the class described the combination of an outer cylindrical wall, a top, an inner cylindrical wall depending from the said top concentrically in spaced relationship to the outer cylindrical wall, means for tangentially introducing air to be cleaned into the top portion of the annular space between the inner and outer cylindrical walls, an outlet pipe passing concentrically through the top and extending above and below said top, means including a scroll casing connected to the outlet pipe above the top and communicating with the interior of the outlet pipe and adapted for connection with an air exhauster, a liquid tight collector basin forming a bottom for the outer casing, means to supply liquid selectively to the top inner circumferences of said inner and outer casing walls, a vertically adjustable overflow pipe extending upwardly through the collector basin and terminating above the top thereof, an outer cylinder disposed intermediate the outer and inner cylindrical walls adjacent the bottom thereof, an inner cylinder disposed concentrically in spaced relation to the inner cylindrical wall, an annular water baffle secured interiorly of the inner cylindrical wall in overhanging relation to the space between the said inner cylindrical wall and said inner cylinder and an air baffle disc supported horizontally intermediate said water baffle and the bottom of the outlet pipe.

4. A combined dry and wet separation air cleaner comprising a cylindrical upright casing, a bottom on the casing, a liquid pool contained by said bottom and providing a deformable liquid floor entirely across the lower end of the casing, a closed top on said casing, an outlet pipe extending through the center of said top for a distance above and below the latter, means adapted to exhaust air tangentially from the outlet pipe, means to tangentially introduce air to be cleaned into the upper circumferential portion of the casing, a cylindrical skirt depending from the top will into the liquid pool whereby the interior of the casing is divided into an annular chamber and a cylindrical chamber surrounded thereby, a pair of upright annular baffles disposed respectively in the bottom portions of the annular and cylindrical chambers and spaced concentrically from relatively opposite faces of said skirt and depending for a distance below the surface of the pool and below the bottom edge of the skirt, wholly submerged baffles traversing

the pool below the said annular baffles, an annular baffle member secured to the inner circumference of the skirt in closely overhanging relation to the top edge of the upright baffle in the cylindrical chamber and presenting an inverted V-groove above the said top edge, and an overflow pipe extending upwardly through the pool from the bottom exterior of the casing into the bottom center area of the cylindrical chamber surrounded by the upright baffle in the latter.

5. In an air cleaning dust collector, an inner and an outer centrifugal collector disposed concentrically one within the other and divided by a common depending cylindrical wall, a basin forming a closure across the bottom of the outer collector and disposed below the lower free edge of said depending wall, a body of liquid in the basin defining between its top and the bottom edge of the depending wall a vertically limited communication between the lower ends of said collectors, an inner cylinder having its lower edge submerged for a distance in said liquid and extending concentrically in inwardly spaced relation for a distance above the bottom depending edge of said common wall, an annular inverted V-trough carried by the inner surface of said common wall in slightly spaced relation to the top of the cylinder and overhanging the latter, a second cylinder submerged in said liquid at its bottom and concentrically spaced outwardly of the common wall, transverse baffles extending across the basin and wholly submerged below the bottom of the inner cylinder, means to introduce air to be cleaned tangentially into the upper portion of the outer collector, and means to exhaust air tangentially from the upper portion of the inner collector.

6. In an air cleaner apparatus of the class described the combination of a pair of centrifugal separators disposed one within the other and separated by a common wall, a scroll casing connected with the air outlet of the inner separator and connectible with air exhausting means for extracting air tangentially from said inner separator, means to admit air to be cleaned tangentially into the upper portion of the outer separator, a liquid pool in the apparatus with the top surface of said pool forming a common floor for both of said separators, endless baffles disposed in concentric relation at opposite sides of said common wall and extending for a distance above and below the surface of the liquid pool, submerged baffles in the liquid pool below and transversely of the said endless baffles, and an inverted V-grooved baffle connected to the inner face of the common wall and in closely overhanging relation to the top edge of the endless baffle in the inner separator.

7. In an air cleaner apparatus of the class described the combination of a pair of centrifugal separators disposed one within the other and separated by a common wall, a scroll casing connected with the air outlet of the inner separator and connectible with air exhausting means for extracting air tangentially from said inner separator, means to admit air to be cleaned tangentially into the upper portion of the outer separator, a liquid pool in the apparatus with the top surface of said pool forming a common floor for both of said separators, endless baffles disposed in concentric relation at opposite sides of said common wall and extending for a distance above and below the surface of the liquid pool, means to provide a selective liquid flow over the major inner surface of the separators,

submerged baffles in the liquid pool below and transversely of the said endless baffles, and an inverted V-grooved baffle connected to the inner face of the common wall and in closely overhanging relation to the top edge of the endless baffle in the inner separator.

8. In an air cleaner apparatus of the class described the combination of a pair of centrifugal separators disposed one within the other and separated by a common wall, a scroll casing connected with the air outlet of the inner separator and connectible with air exhausting means for extracting air tangentially from said inner separator, means to admit air to be cleaned tangentially into the upper portion of the outer separator, a liquid pool in the apparatus with the top surface of said pool forming a common floor for both of said separators, endless baffles disposed in concentric relation at opposite sides of said common wall and extending for a distance above and below the surface of the liquid pool, means to selectively provide a liquid flow downwardly over the major inner surface of the separators, a vertically adjustable overflow pipe ex-

tending from the lower central portion of the inner separator through the bottom of the apparatus, submerged baffles in the liquid pool below and transversely of the said endless baffles, and an inverted V-grooved baffle connected to the inner face of the common wall and in closely overhanging relation to the top edge of the endless baffle in the inner separator.
